United States Patent Office.

ROBERT D. STERLING, OF NEW YORK, N. Y.

Letters Patent No. 70,129, dated October 22, 1867.

IMPROVED JOINT-BIT AND CHECK.

The Schedule referred to in these Letters Patent and making part of the same.

TO ALL WHOM IT MAY CONCERN:

Be it known that I, ROBERT D. STERLING, of New York, in the county and State of New York, have invented a new and useful "Joint-Bit and Check;" and I do hereby declare that the following is a full and exact description of the same, reference being had to the accompanying drawing, and to the letters of reference marked thereon.

Figure I represents the bridle complete attached on the horse.

Figure II is a front view of the bridle.

This invention consists in the arrangement of the check-reins, and the manner of attaching the same to the bit, whereby greater control can be had over the horse, and it is almost impossible for the horse to hold the bit fast between his teeth.

In the accompanying drawings the crown-piece A, brow-band B, cheek-pieces C, and throat-band D, are constructed in the usual manner similar to any common bridle. The mouth-piece E is made in three pieces, *a*, *a*, and *b*, jointed together, the parts *a a* having the cheek-rings *m* attached, to which the cheek-pieces C and the reins F are fastened. On the pieces *a a* of the bit, loose rings J are placed, to which reins *n n* are attached passing over the horse's nose, and connected together by the ring *e*. To the upper end of this ring *e* the check-reins G are attached, passing over the horse's head, through guides *d* fast to the crown-piece A, and pass then on each side of the horse's neck, and are, near the end, joined together again and fastened there to the hook *i* in the harness H. The rings J are placed perfectly loose on the bit or mouth-piece E, inside of the cheek-rings *m*, so that said mouth-piece may be operated through the reins F in the usual manner. Each ring has an ear or loop to which the rein and strap are attached instead of directly to the ring. By this device any working of the ring is prevented, and consequently there is no danger of hurting the sides of the horse's mouth. When the check-reins G are used to control or manage the horse, the strain brought to bear on the mouth-piece E will cause the rings J to move nearer together, and at the same time slide on the outer joints *a a* towards the central joint *b*, causing thereby these joints to take a position, thus in the horse's mouth, whereby a great power is obtained over the horse. It will be readily understood that these rings J and check-reins G may be applied to the bridoon-bit, port-mouthing bit, snaffle-bit, or any other description of bit that may be desired.

What I claim as my invention, and desire to secure by Letters Patent, is—

The straps *n* suspended from the top ring *e*, and connected to the loop-ring J sliding on the linked bit *a b c*, constructed and operating as and for the purpose described.

ROBERT D. STERLING.
